Otto G. Rieske, Buffalo, N. Y.

Application July 27, 1944, Serial No. 114,581

Term of patent 14 years

(Cl. D11—1)

To all whom it may concern:

Be it known that I, Otto G. Rieske, a citizen of the United States, residing at Buffalo, in the county of Erie and State of New York, have invented a new, original, and ornamental Design for a Fish Scaling Device, of which the following is a specification, reference being had to the accompanying drawing forming a part thereof.

In the accompanying drawing Figure 1 is a perspective view of the fish scaling device embodying my design. Figure 2 is a rear end view thereof. Figure 3 is a front end view of the same.

I claim:

The ornamental design for a fish scaling device, substantially as shown.

OTTO G. RIESKE.
